PADLOCK

Richard J. Ohno, North Branford, Conn., assignor
to Sargent & Company, New Haven, Conn., a
corporation of Connecticut

Application November 11, 1943, Serial No. 509,821

10 Claims. (Cl. 70—38)

This invention relates to padlocks, and more particularly to a padlock made up of a plurality of superposed plates or sections which form the body of the lock and house the locking mechanism. It will be understood, however, that certain features of the invention may be employed in connection with locks other than padlocks, although, in the present instance, they are illustrated as applied to a padlock.

In the construction of a padlock having a laminated body or case formed of superposed plates or sections, it is desirable to provide lock mechanism of such form that it may be readily accommodated to the thickness of one or more of the sections and at the same time be readily installed or assembled, as the sections are built up, one upon the other. This applies not only to the locking member or bolt which cooperates with the shackle to hold it in locked position but also to the means for preventing the complete detachment of the shackle from the lock when the shackle is open, and in addition to the key-operated lock mechanism which serves to rotate the bolt.

It is contemplated by the present invention to improve the various features above referred to, with particular reference to the means for securing the shackle against complete detachment from the lock and to the means for securing the key barrel in the housing of the key-operated lock mechanism.

One object of the invention is to provide a padlock having a laminated body made up of a plurality of superposed sections or plates and having novel means for securing the shackle against detachment from the lock.

A still further object of the invention is to provide a padlock having a key-operated locking member cooperating with the shackle and mechanism for operating this member, including a lock housing and key barrel, with improved means for retaining the key barrel within the housing, and at the same time providing a stop to limit the rotation of the key barrel.

A still further object of the invention is to provide a lock mechanism having a lock housing and a key barrel rotatably mounted therein, with a combined securing and limiting member which will function satisfactorily to retain the key barrel in place within the lock housing and also serve as a means of limiting the rotation of the key barrel.

Still another object of the invention is to provide a padlock having a body of laminated form with a member extending transversely of the case

and engaging at its intermediate portion with a shoulder extending transversely of the shackle to prevent complete detachment of the latter from the case, which member, in the form shown, is resilient or a spring member to yield upon rotation of the shackle.

To these and other ends, the invention relates to the novel features and combinations of parts to be hereinafter described and claimed.

In the accompanying drawing:

Fig. 1 is a front elevational view of a padlock embodying my invention;

Fig. 2 is a top plan view of the same;

Fig. 3 is a bottom plan view of the lock;

Fig. 4 is the central longitudinal section through the lock, some parts being shown in full lines;

Fig. 5 is a sectional view on line 5—5 of Fig. 4;

Fig. 6 is a sectional view on line 6—6 of Fig. 4;

Fig. 7 is a sectional view on line 7—7 of Fig. 4; and

Fig. 8 is a sectional view on line 8—8 of Fig. 4.

To illustrate a preferred embodiment of my invention, I have shown a padlock comprising a case or lock body 10 of laminated form made of a plurality of superposed sections which will be described in detail hereinafter. These sections, as will be explained, are of various conformations, particularly with respect to the openings therein which receive the working parts of the lock. It will be understood that the plates are all of the same exterior pattern, however, so that when superposed and firmly secured together the lock body will have a smooth outer surface.

In the present instance, the bolt of the lock is designed to be operated by a pin tumbler locking mechanism and the plates are arranged to receive a structure of this kind. It will be understood, however, that the lock is not limited to a locking mechanism of this character. This mechanism comprises the usual key barrel 11, rotatably mounted within a housing 12 having a pin tumbler extension 13. It will be noted from Figs. 7 and 8, for example, that the key barrel 11 is provided with an enlarged head 14 on its lower end and with a reduced neck 15 a short distance below its upper end and a portion 13a of normal size above the neck.

This reduced neck is flat upon two sides, as shown at 16 and 17 in Fig. 7, and is adapted to be closely embraced by a disk 18 slotted to receive snugly the neck 15. It will be apparent from Fig. 8 that the disk 18 is of sufficient size to overlie the upper end of the housing 12 around the key barrel and that this disk, in connection with the

head 14 (which lies below the housing 12), will effectually hold the key barrel in place, the disk 18 rotating with the key barrel. It may also be noted that the disk 18 is provided with a projecting lug 19 which serves as a stop or limiting member, as will be hereinafter described.

The upper end of the key barrel is reduced in size, as shown at 20, and is of non-circular form to be received in an opening 21 in an oscillating locking member 22, the ends 23 and 24 of which cooperate with recesses 25 and 26 in the shackle 27 to retain the shackle in locked position, as will be clear to those skilled in the art.

One leg of the shackle 27 is longer than the other, this longer leg 28 extending downwardly to a position adjacent the bottom of the case where it is provided with an annular recess or groove 29 and with a lateral recess 30 at one side, forming a flattened face. Below the recess 29, is a head 31, against which bears a spring 32 to urge the shackle to open position.

As will be apparent when the locking member 22 is rotated or oscillated, so as to disengage its ends 23 and 24 from the recesses 25 and 26, the spring 32 would tend to force the longer leg of the shackle from the opening in which it rests and thus detach the shackle completely from the lock. This, however, is prevented by means of a retaining member 33, shown more especially in Figs. 6 and 7, which retaining member extends transversely across the lock case, lying in an opening in the plates forming the case, and bears at its intermediate portion against the flat face 30 of the shackle leg 28. The member 33 is sufficiently resilient so that the shackle may be rotated when it is in open position, the member 33 yielding at its central portion to permit this action. Normally, however, such rotation will occur when the shackle is in its full open position and the spring 33 lies within the annular recess 29 and, at this time, the spring engages the upper surface of the head 31 to retain the shackle connected to the lock case.

The various sections which go to make up the lock case will now be described. The two upper sections, designated by the letter *a*, are identical in form and are of the shape shown in Fig. 2, containing a circular opening adjacent each end for reception of the shackle. The next two lower plates are designated by the reference character *b* and are of the form shown in Fig. 5. These plates are provided with central openings of irregular shape, these openings providing a chamber for the locking member 22, the chamber being sufficiently spacious to permit this member to oscillate. These plates are also provided with shoulders 35 against which bears a spring 36 acting at its other end against a shoulder 37 on the locking member 22 to normally urge this member to locked position, as shown in Fig. 5. The next lower plate, designated by the reference character *c*, is shown in Fig. 6 and, as will be apparent, it is provided with an opening of irregular shape to receive the spring 33, one leg of the shackle, and the upper end of the key barrel. The next lower section *d* is formed as shown in Fig. 7 and is provided with an opening of irregular shape, as shown at 39, this opening being adapted to receive the longer leg of the shackle, the spring 33, the disk 18, and a portion of the key barrel embraced thereby, and also a part of the housing of the pin tumbler lock. It may here be noted from reference to Fig. 7 that the pin tumbler extension 13 of the housing 12 is provided with an upstanding member or lug 40 designed to be en-

gaged by the lug 19 to form a stop for the rotation of the key barrel in one direction. The rotation of the key barrel in the other direction is limited by a portion 41 of the plate *d* which engages the opposite face of the lug 19.

Below the plate or section *d* are a plurality of plates *e* of identical form. Each of these plates is provided with a relatively large opening of the proper size and shape to receive the pin tumbler lock housing 12 and extension 13, and with a small circular opening to receive the leg 28 of the shackle and the spring 32.

The lowest section or plate *f* is of the form shown in Fig. 3 and is provided with a single circular opening to receive the head 14 of the key barrel. It will be understood, however, that all of the plates are provided with openings to receive rivets 42 by which the sections are secured together to form a rigid body of smooth exterior outlines. It will also be apparent that the spring 33 is held in position by having its ends lodged between portions of the openings in the plates *c* and *d*, and particularly between the edges of these openings and the posts 42, so that the ends of the spring will be held fairly rigidly against movement.

The device is shown in locked position in Figs. 4, 5, and 7 of the drawing where it will be seen the ends 23 and 24 of the bolt are engaged in the recesses 25 and 26. If a key is inserted in the lock and the key barrel operated in a counter-clockwise direction as viewed in Figs. 5 and 7, the bolt will be disengaged from the shackle and will permit the shackle to be moved outwardly by the spring 32. The bolt 22 is rotated against the action of the spring 36 and the lug 19 is moved from a position against the member 40, as shown in Fig. 7, to a position against the edge 41 of opening in the plate *d*. When the shackle has been moved outwardly by the spring 32, the longer leg 28 thereof will retain the bolt 22 in its unlocked position by engagement with the side surface of the end 24 of the bolt. The shackle may now be rotated with respect to the casing 10, if desired, in order to free it from the hasp or other element with which it has been engaged.

Although the bolt 22 will be held in position to which it has been rotated, the key barrel may be returned to its original position so as to align the tumblers (not shown) to permit removal of the key by reason of the fact that the opening 21, as shown in Fig. 5, has enlarged ends which will permit relative movement between the bolt and the upper reduced portion 20 of the key barrel. If it is desired to return the shackle to locked position, the short end thereof may be brought opposite the opening in which it is received and the shackle pressed downwardly. When it reaches the position shown in Fig. 4, the bolt will be returned by the spring 36, to the position shown in Fig. 5.

While I have shown and described a preferred embodiment of my invention, it will be understood that it is not to be limited to all of the details shown, but is capable of modification and variation within the spirit of the invention and within the scope of the appended claims.

What I claim is:

1. A padlock comprising a case having shackle openings therein, a shackle cooperating with the case and having a long and a short leg received in said openings, said long leg having a shoulder adjacent the lower end thereof, and a flat resilient member extending transversely across one end of the case through one of said openings and

urged against the side of said long leg to engage said shoulder and prevent detachment of the shackle from the case.

2. A padlock comprising a case, a shackle cooperating with the case and having a long and a short leg, said long leg having a shoulder adjacent the lower end thereof, a flat resilient member extending transversely across one end of the case and urged against the side of said long leg to engage said shoulder and prevent detachment of the shackle from the case, and said case comprising a series of superposed plates and rivet members holding said plates together, said member bearing at its ends against certain of said rivets.

3. A padlock comprising a case, generally oblong in shape and having a shackle opening adjacent each end thereof, and a shackle member cooperating with the case and having a long leg and a short leg received in said openings, said long leg having a flattened portion adjacent its lower end and a shoulder below said portion, and a flat spring member extending transversely across one end of the case and bearing at its intermediate portion against said flattened portion of the shackle and engaging said shoulder to prevent detachment of the shackle from the case.

4. A padlock comprising a case, generally oblong in shape and having a shackle opening adjacent each end thereof, and a shackle member cooperating with the case and having a long leg and a short leg received in said openings, said long leg having a flattened portion adjacent its lower end and a shoulder below said portion, a flat spring member extending transversely across one end of the case and bearing at its intermediate portion against said flattened portion of the shackle and engaging said shoulder to prevent detachment of the shackle from the case, said case comprising a plurality of superposed plates, and said spring being disposed in openings in certain of said plates.

5. A padlock comprising a case formed of a plurality of superposed plates having openings therein to provide a chamber, a lock housing seated in said chamber, a key barrel rotatably mounted in the lock housing and extending therefrom at one end, said key barrel having a reduced portion on said end and an enlarged portion beyond said reduced portion, a retaining element non-rotatably embracing said reduced portion and engaging the housing to retain the key barrel therein, said element having a projecting lug, and stop means to engage said lug to limit rotation of the key barrel.

6. A padlock comprising a case formed of a plurality of superposed plates having openings therein to provide a chamber, a lock housing

seated in said chamber, a key barrel rotatably mounted in the lock housing and extending therefrom at one end, said key barrel having a reduced portion on said end and an enlarged portion beyond said reduced portion, a retaining element non-rotatably embracing said reduced portion and engaging the housing to retain the key barrel therein, said element having a projecting lug, and said element being disposed within the opening in one of said plates.

7. A padlock comprising a case formed of a plurality of superposed plates having openings therein to provide a chamber, a lock housing seated in said chamber, a key barrel rotatably mounted in the lock housing and extending therefrom at one end, said key barrel having a reduced portion on said end, a retaining element non-rotatably embracing said reduced portion and engaging the housing to retain the key barrel therein, said element having a projecting lug, and stop means engaging said lug on both sides thereof to limit rotation of the key barrel in either direction.

8. A padlock comprising a case formed of a plurality of superposed plates having openings therein to provide a chamber, a lock housing seated in said chamber, a key barrel rotatably mounted in the lock housing and extending therefrom at one end, said key barrel having a reduced portion on said end, a retaining element non-rotatably embracing said reduced portion and engaging the housing to retain the key barrel therein, said element having a projecting lug, and a stop member on said housing to engage said lug and limit rotation of the key barrel.

9. A padlock comprising a case formed of a plurality of superposed plates having openings therein to provide a chamber, a lock housing seated in said chamber, a key barrel rotatably mounted in the lock housing and extending therefrom at one end, said key barrel having a reduced portion on said end, an element non-rotatably embracing said reduced portion and having a projecting lug, a stop member on said housing to engage said lug and limit rotation of the key barrel, and means on one of said plates to engage said lug and limit rotation of the key barrel when the lug is turned away from said stop member.

10. In a lock, a housing and key barrel rotatably mounted in the housing, said key barrel having a reduced end portion projecting from the housing and an enlarged portion beyond said reduced portion, a slotted disk non-rotatably embracing said portion, said disk having a lateral projecting lug thereon, and means on the housing engaging said lug to limit rotation of the key barrel.
